Des. 232,052

Patented July 9, 1974

232,052

MULTIPLE TAPE MEASURE

Michel Quenot, Zone Industrielle Trepillot,
F-25 Besancon, France

Filed Jan. 5, 1972, Ser. No. 215,708

Claims priority, application France July 12, 1971

Term of patent 14 years

Int. Cl. D10—04

U.S. Cl. D52—6 A

FIG. 1

FIG. 2

FIG. 3

FIG. 1 is a top perspective view of a multiple tape measure showing my new design in which the measuring blades are shown both in retracted and partially extended position.

FIG. 2 is a bottom perspective view thereof.

FIG. 3 is a side elevational view thereof.

I claim:

The ornamental design for a multiple tape measure, substantially as shown and described.
